STEREO CAMERA

John J. Hughes, Jr., Milwaukee, Wis., assignor to Stereo Corporation, Milwaukee, Wis., a corporation of Wisconsin

Application May 18, 1956, Serial No. 41,536

Term of patent 14 years

(Cl. D61—1)

Fig. 1

I claim:

The ornamental design for a stereo camera, substantially as shown.
